ELECTRIC TRANSLATING DEVICE

Florenz J. von Delden, Los Angeles, Calif., assignor to Vedee Corporation, Los Angeles, Calif., a corporation of Delaware

Application April 15, 1937, Serial No. 137,023

12 Claims. (Cl. 230—55)

This invention relates to electric translating apparatus and especially to such apparatus in which electrical pulsations are translated into reciprocating motion.

One of the objects of the invention is to provide an apparatus for translating electrical pulsations into mechanical movement with a high degree of efficiency.

Another object of the invention is to provide a highly efficient reciprocating motor with few moving parts.

Another object of the invention is to provide an efficient reciprocating motor in which the length of stroke may be adjusted with load conditions.

Another object of the invention is to provide a reciprocating motor in which the noise level is maintained at a minimum.

Another object of the invention is to provide a reciprocating compressor with novel lubricating and cooling means.

Still another object of the invention is to provide an electric refrigerator in which the compressor for the refrigerant is operated by a reciprocating electric motor.

Still another object of the invention is to provide a reciprocating electric motor which will operate on alternating current.

Other objects and objects relating to the method of constructing and assembling the various parts will be apparent as the description of the invention proceeds.

The invention is illustrated in the accompanying drawings, in which:

Fig. 1 is a plan view, partly in section, of one form of motor for translating electrical pulsations into reciprocating motion, together with a circuit diagram of the connections;

Fig. 2 is a similar plan view, partly in section, of a motor adapted to operate on raw alternating current;

Fig. 3 is a side elevational view, partly in section, of a fluid compressor embodying the invention;

Fig. 3a is an enlarged elevational view of one of the electrical connectors used with the device of Fig. 3;

Figs. 3b and 3c are plan and sectional elevational views respectively of one form of piston valve;

Fig. 3d is a plan view of a modified form of piston valve;

Fig. 3e is a fragmentary sectional view of a portion of the piston skirt;

Fig. 3f is a fragmentary sectional end view of a modified form of piston assembly;

Fig. 4 is a sectional side elevational view of a refrigerator with the compressor unit of Fig. 3;

Fig. 5 is a diagram showing the electrical and gas connections for the compressor of Figs. 3 and 4;

Fig. 5a is a portion of the diagram of Fig. 5 showing a modification thereof;

Fig. 6 is a diagram showing a modified electrical circuit;

Fig. 7 is a side elevational view, partly in section, of a double-acting compressor using the principle of the invention;

Fig. 8 is a sectional end view of the compressor unit of Fig. 7, taken on the line 8—8 of that figure;

Fig. 9 is a circuit diagram showing an alternative connection for the moving coil of Figs. 7 and 8;

Fig. 10 is a sectional side elevational view of a diaphragm type of compressor embodying the invention;

Fig. 11 is a sectional plan view of the compressor of Fig. 10, taken on the line 11—11 of that figure;

Fig. 12 is an elevational view, partly in section, of a bellows type compressor embodying the invention; and

Fig. 13 is a sectional, elevational view of still another modified form of dynamic motor.

In Fig. 1 a simple arrangement is shown for utilizing the invention and in which electrical pulsations or alternations are translated into reciprocating motion. In order to accomplish this result I provide an annular magnetic field between a cylindrical core 10, which acts as one pole of the magnet, and a plate 11 having a hole 12 therein to receive the end of the core, which acts as the other pole. A coil 13 of wire may surround the enlarged end 10a of the core 10 and the magnetic circuit may be completed by a U-shaped member 14 of magnetic material, to the central portion of which the enlarged end of the core 10 may be secured by any desired means, as by the shank 15 fitting tightly into a hole 16. The plate 11 may then be fastened to the ends of the U-shaped member 14 in a suitable manner, as by means of screws 17.

I prefer to have the end of the core 10 extend outwardly slightly beyond the plate 11 and to provide a groove 11a around the surface thereof at a point about even with the inner edge of the hole 12. This groove may have a width about equal to one quarter of the thickness of the plate

and may have about an equal depth. The coil 13 may be securely held in place by the plate 11, a suitable insulating packing ring 13a being positioned between the plate and coil. The shoulder 5 10b on the enlarged portion 10a may be preferably chamfered, as indicated, so as not to cut into the coil 13.

A closely wound coil 18 of wire may be mounted for reciprocation in the annular field by means 10 of a cylindrical support 19 which may be made of aluminum, if desired, or some other non-magnetic material, such as stiff paper, and upon which the coil may be cemented or otherwise attached. The support member 19 may have an 15 end wall 20 which may be rigidly attached to a shaft 21 mounted for reciprocation in a bearing 22. The opposite end of the shaft 21 may be provided with a bifurcated connection 23 to which may be attached any mechanism to be 20 driven by the reciprocating motor, as, for instance, pumps, riveters, or the like, or the reciprocations may be translated into rotary motion in a manner which will be clearly understood.

25 When the coil 13 is energized by direct current an intense magnetic field is set up in the air space between the plate 11 and the magnetic core 10. When an alternating current is passed through the coil 18 a magnetic field is set up 30 around the coil which is at right angles to the direct current field and causes the coil to move in one direction for one-half of the alternating current cycle and in the other direction for the other half. Thus the coil is caused to reciprocate in the field and carries with it the supporting member 19 and the shaft 21, and thus reciprocates any mechanism connected to it.

In order to permit this apparatus to operate 40 on alternating current power mains I may provide a transformer 32 having a primary winding 33 and three secondary windings 34, 35 and 36. A rectifier tube 37 may have its filamentary cathode 38 energized by means of the winding 34, while the two anodes 39 and 40 may be connected 45 to the ends of the coil 35. The center tap of the coil 35 may be connected to one side of the coil 13, while the other side of the coil may be connected to the filamentary cathode 38. A pair of filter condensers 41 and 42 may be connected 50 across the leads to the coil 13 to filter out pulsations produced by rectification, as will be understood by those skilled in the art. With this arrangement the coil 13 is provided with direct current when the transformer 32 is energized.

55 In order to provide the coil 18 with alternating current I connect it to the secondary winding 36, preferably using a potentiometer 43 to control the amount of current flowing in the coil 18. With the potentiometer connected as shown, across the 60 secondary 36, with the coil 18 connected between the arm 43a of the potentiometer and one side thereof, it is possible to adjust the voltage on the coil 18 from zero to the maximum voltage produced by the secondary 36. This adjustment of 65 voltage of the coil 18 provides a means to control the force which is acting on the coil 18, and thus a means to adjust the power of the motor.

Under some conditions it may be desirable to 70 dispense with the rectifier tube and transformer 32, described in connection with the last figure, and operate the field coil on alternating current. An arrangement for doing this is shown in Fig. 2. The same principle of the reciprocating coil is used in this figure in which a U-shaped magnetic member 50 may be provided with a coil 51 sur-

rounding the central pole piece 52, the latter being attached to the housing 50 at the center, similarly to that described in connection with Fig. 1, the plate 53 having a hole 54 in the center thereof to receive the end of the pole piece 52. The ends 5 of the plate pole piece 53 may be attached to the ends of the member 50 by means of suitable screws 55.

Also, similarly to the construction of Fig. 1 the coil 56 may be supported in the air gap between 10 the pole piece 52 and the plate 53 by means of a cylinder 57, of aluminum or other light weight non-magnetic material, which may be secured to the shaft 58 supported for reciprocation in the bearing 59. This shaft may terminate in a bifurcated member 60 which may be attached to the mechanism to be driven. A compression spring 61 may be mounted around the shaft 58, between the bearing 59 and the cylinder 57, so that the shaft and cylinder may be urged by the action 20 of the spring towards the right with the coil at its farthest position in the magnetic field.

The coil 51 is intended to be energized directly by alternating current received from the 110 volt power mains. In order to energize the coil 56, 25 however, I may provide another coil 68 wound on the core 52 and having a considerably smaller number of turns than the coil 51. This coil may act as a transformer secondary having current at a lower voltage (for instance, 25 volts) induced 30 in it from the coil 51. The coil 68 may therefore be connected to the moving coil 56, preferably by means of a potentiometer 69, which may be used to control the voltage of the coil and therefore 35 to adjust the power of the motor.

The alternating current in the coil 51 causes 40 the field to alternate. At the same time, the current in the coil 56 is alternating; hence the force tending to move the coil 56 is always acting in the same direction. Connections to the coil 56 are 45 made so that the proper phase relation is obtained between the current in the two coils which will cause the coil 56 to move in an outwardly direction or towards the left, as shown in Fig. 2, for each half of the alternating current cycle. As 50 the coil moves against the action of the spring 67, the spring will return the coil to its innermost position again when the force causing it to move approaches zero or at each half of the alternating current cycle.

It will be seen from the above arrangement that 55 the device of Fig. 2 may be operated directly on alternating current without the use of any rectifier or filter circuit. The pole pieces may be made laminated, if desired, to reduce heating effects.

An important use for the reciprocating motor itself may be to operate a reciprocating device, such as a compressor, which might be used in an electrical refrigerating apparatus. Such a compressor may consist merely of a reciprocating 60 piston attached to the coil and may thus eliminate all rotating parts.

In Fig. 3 I have shown such a compressor adapted to be used in an electric refrigerator. In this figure a magnetic U-shaped member 75 has a core member 76 attached to it, as by means of the shank 77 on the lower end of the core which may be threaded into a hole 78 in the member 75 to form a rigid connection. A coil 80 may 70 surround the core 76 to energize it, and a plate 81 may be provided with a hole 82 to fit over the upper end of the core 76 and leave an air space between it and the core. The plate 81 may rest upon the top of the two legs of the member 75

and may be secured by means of screws, or in any other desired manner, such as by welding.

The core member 76 may extend slightly above the plate 81 and may have an enlarged lower portion 83 around which the coil 80 may be wound. Also I prefer to provide a groove 76a around the core member about even with the lower edge of the plate 81 and having a width and depth about equal to one quarter of the thickness of the plate. This groove appears to aid in concentrating the magnetic flux in the annular space between the plate and the end of the core 76.

The coil 80 may be rigidly held in place by the plate 81 with a gasket 80a between the plate and the coil which makes a substantially liquid tight seal between the coil and plate for a purpose to be hereinafter described.

The cylinder 84 for the compressor may be mounted upon the top of the plate 81 by means of four legs 85, which may extend outwardly and downwardly from the sides thereof, and have feet 86 which may be secured to the plate 81 by means of suitable screws 87. A valve disc 88 may rest on top of the cylinder, a suitable gasket being provided in between the cylinder and disc, and this disc may carry a pair of thin spring steel valves 89 adapted to overlap each other on top of the disc and to cover a hole 90 in the disc. The valves may be held in position by means of the screws 91.

On top of the disc 88 I provide a dish-shaped head 92 which may be made slightly larger in diameter than the disc 88 with a flange to fit over the disc, a suitable gasket being used in between. A pipe connection 93 may be formed integral with the head communicating with the under side thereof to form the outlet for the compressor.

The head 92 may be secured in place by means of a yoke 94 which may be anchored to the cylinder by rods 95, the rods having threaded lower ends which engage tapped holes in the upper part of the legs, as shown, and threaded upper ends which may be provided with securing nuts 95a. A set screw 96 at the center of the yoke may engage a recess 97 on the top of the head, and by tightening the set screw the head 92 and valve disc 88 will be forced securely against the top of the cylinder. If desired, a second set screw 98 may be used to lock the first one.

The piston 99 may comprise a hollow casting, preferably of aluminum, which may have a cylindrical portion 100 at its upper end adapted to have a sliding fit in the cylinder 84. The lower end of the portion 100 may have a plurality of large ports 101 which may form the inlet ports for the compressor.

A thin steel disc valve 102 (Figs. 3b and 3c) may be secured on the top of the piston by means of a central bolt 103 and may cover the openings 104 in the top thereof. In order to insure the operation of this valve I preferably undercut the head of the bolt 103 as at 103a which causes the periphery of the disc to rise slightly away from the top surface of the piston and reduces the tension of the edge of the disc thereagainst. For use with a less dense gas I may prefer to use the valve illustrated in Fig. 3d where a thin steel cross 104a is used in place of the disc, the ends of the cross covering the holes in the top of the piston.

Below the ports 101 the piston may be somewhat larger in diameter and may be provided with a skirt 104b which may extend into the

annular space between the pole piece 76 and the plate 81, and have a reduced section 105 to receive the wires of the coil 106.

I may compensate for the weight of the piston and the pressure of the gas above it by means of a coil spring 99a inside the piston and secured to the top of the piston by the valve bolt 103 and to the pole piece 76 by a suitable screw 100a.

When the winding 80 is energized by direct current, producing an intense field across the air space between the plate 81 and the core member 76, and alternating current is run through the coil 106, movement of the coil will result, thereby reciprocating the piston in the cylinder.

Fluid is introduced into the compression space of the cylinder through the openings 101 in the piston and the spring valve 102 in the top thereof. Fluid leaves the cylinder through the flap valves 89 in the disc 88 and the outlet connection 93 in the head 92.

In order to make the electrical connections for the moving coil I may use a pair of resilient connectors 107 extending between the skirt 104 of the piston and insulating blocks 108 mounted on the outermost edge of the plate 81. Each of the connectors 107 (Fig. 3a) may comprise one or more corrugated ribbons, preferably one, 109, of phosphor bronze and, if additional support is required, one or more others, 110, of steel, laid one upon the other with the outer ends secured to the insulating block 108 by means of a screw 111, the screw also holding a lug 112 to which the connection may be made. The inner end of the connector 107 may be bent upwardly and secured to the piston skirt 104b by a rivet or bolt 114 (Fig. 3e) and insulated therefrom by suitable insulating washers 115. The corrugations on these connectors are sufficient to permit rapid reciprocation of the piston without breaking the connectors, but in order to insure against breakage I may provide limiting guides 107a and 110a (Fig. 3a) at the outer and inner ends of the connectors which are curved, as shown, to prevent sharp bends in the connectors when in operation.

The ends of the coil 106 may be connected to the inner ends of the connectors 107, as shown in Fig. 3a. To do this I preferably provide grooves 109a (Fig. 3e) in the skirt 104b in which the wires may be cemented, the wire for the lowermost end of the coil thus passing under the turns thereof.

Inasmuch as the connector applies a slight sidewise force against the piston when the piston reciprocates, I prefer to use two connectors, one opposite the other, so that these effects will be balanced out. However, under certain conditions, I may dispense with one connector entirely and ground one end of the coil directly to the piston so that one side of the transformer secondary supplying current to the coil may be attached to any portion of the motor or container, while the other side of the coil will be fed through the resilient connector.

I may desire to operate the compressor with its driving mechanism as shown inside of a drum or container 116 which also may act as a reservoir for lubricating oil and the refrigerating fluid. This container 116 may comprise a lower compartment 117 in which the magnetic member 75 may resiliently rest upon coil springs 118 provided for that purpose. In order to support the springs I may prefer to mount the whole dynamic motor upon a plate 119 which may be screwed or otherwise attached to the magnetic member 75 and which may be provided with lugs 120 around

which the springs 118 may fit. Corresponding lugs 121, spotwelded or otherwise attached inside the compartment 117 to the bottom thereof, may receive the lower ends of the springs. An upper compartment 122 may be sealed to the lower compartment by means of flanges 123 and 124, respectively, formed on the upper and lower compartments and held together by means of screws 125, a suitable gasket 126 being used to make a gas-tight connection and stiffening rings 127 and 128 being used, if desired, above and below the flanges.

In order to provide lubrication for the moving piston I prefer to substantially fill the lower compartment 117 with some lubricating oil 129, such as Russian mineral oil, so that the field coil 80 and moving coil 106 operate in the oil as well as the lower skirt 104b of the piston. Reciprocation of the piston will cause oil to splash up and lubricate the upper portions thereof. The rapid movement of the coil 106 in the circulating oil prevents the coil from overheating and permits the use of a much larger current in the coil than would be possible otherwise with the same size wire. This aids in maintaining a high degree of efficiency, as the more current that can be passed through the coil the greater will be the power generated.

The upper compartment 122 of the container 116 may be provided with an inlet connection 130 by means of which the refrigerant may enter it, and an outlet connection 131 may be provided in the lower compartment 117 and may be connected to the cylinder outlet connection 93 by means of a length of tubing 132 and suitable fittings. The tubing may pass once or twice around the whole motor assembly to give it resiliency to permit movement of the motor within the container.

Vapor then flows into the container 116 through the inlet connection 130 and fills the space above the oil 129. It is therefore free to pass into the piston 99 and up through the valve 102 into the compression space of the cylinder as the piston makes its downward stroke. Movement of the piston in an upwardly direction compresses the vapor inside of the cylinder into gas and forces the compressed gas through the valve disc 88 and the outlet connection 93 in the cylinder and through the pipe 132 and the container outlet connection 131.

Electrical connections may be made to the dynamic motor through the lower wall of the container by means of terminals which may be secured in the wall of the lower compartment 117. Thus a pair of terminals 135 and 136 which are suitably insulated from the walls of the container and which form a gas-tight lead-in through the wall thereof may be used to connect the field winding 80, while a pair of similar terminals 137 and 138 may be used for completing the circuit to the resilient connectors 107 for the moving coil. If one end of the moving coil is connected directly to the piston, only one of the terminals 137 and 138 need be used, the other connection being made to any metal part of the container.

I have found it desirable to eliminate all stray magnetic fields so as to concentrate the magnetic flux as much as possible in the annular space between the central pole and the topplate. Therefore I prefer to make the cylinder 84, the valve disc 88, the head 92, and the yoke 94, as well as the upper part of the container 116 of non-magnetic material, such as brass. I have

found that this not only improves the efficiency of the whole apparatus but also prevents certain difficulties from arising, as, for instance, magnetic sticking of the exhaust valve if the cylinder is made of iron or steel.

In order to have a compressor of high efficiency it is important to have the compression space in the cylinder as small as possible at the end of the compression stroke. Hence the various parts should be so designed that the upper end of the piston closely approaches the valve disc 88 at the upper end of its stroke when operated at maximum power. The strength of the spring 99a is also important in bringing about this condition without knocking of the piston at either end of the stroke.

Inasmuch as the oil in the annular space between the core and the plate is trapped therein by the gasket 80a it has a cushioning effect on the piston which prevents the lower edge of the piston from striking the shoulder of the core on its downward stroke, especially under changing load conditions.

Fig. 3f shows a modified form of the construction wherein further use is made of the oil cushion. Here the core 71a is made similar to the core 76 of Fig. 3 with a groove 77b to receive and trap the oil. However the plate 81a may be provided with ducts 81b and 81c extending through the plate from edge to edge, parallel to 30 and near the under surface thereof. These ducts open into the hole 82a about even with the groove 77b to transmit oil to and from the groove. When the piston skirt 104c moves in the annular space between the plate and core, oil is caused to 35 circulate back and forth through these ducts giving a continuous movement to all the oil in the container 116 which insures cooling of the motor.

If desired, I may provide a hole 82b in the top 40 of the plate communicating with the duct 81c in which may be screwed a pipe 82c which may extend upwardly and be bent at the upper end towards the center of the upper container 122. This pipe may have a nozzle 82d at the upper end 45 so that oil forced through it will be directed against the top of the container 122. A plug 83a having a small hole therethrough may be threaded into the outer end of the duct 81c so that most of the oil forced through the duct 50 will pass up through the pipe 82c although some will pass through the plug.

With this arrangement oil is not only continually circulated about in the lower container 117, but is also sprayed against the inside wall 55 of the upper container 122 so that vibration of this upper container, which would normally be in contact only with the vapor of the refrigerant, is dampered and the noise level of the whole apparatus is thus reduced.

Oil is forced in and out of the duct 81b at the same time the oil is sprayed from the pipe 82c, but if desired a valve 83b may be placed in the outer end of the duct 81b to make this duct always act as the inlet.

In Fig. 3f a modified form of the piston is also shown. The wall 100b between the small end 100d and the skirt 104c may have an angle of about 45° and the upper edges of the core 71a may be chamfered to conform to this angle. The top of the core may be provided with a recess 101a to receive oil, and a plurality of holes 100c may be provided around the top of the piston skirt to let oil out when the piston comes down. I have found that although the oil level is about as in-

dicated by the dot and dash line 129 of Fig. 3, the oil inside the piston rises considerably above the top of the core. The action of the oil coming through the holes 100c dampens the lower end of the piston stroke and reduces the tendency of the piston to strike the core. With this arrangement the coil spring within the piston may in some cases be eliminated.

The modified parts shown in Fig. 3f may be substituted for the corresponding parts of Fig. 3 for use as a compressor in an electric refrigerator.

In Figs. 4 and 5 the compressor of Fig. 3 is shown mounted in a refrigerator 139 having a compartment 140 in the base to house the mechanism and a cold compartment 141 in which the freezing coils 142 may be suspended. A pipe 143 may extend upwardly at the rear of the cabinet to deliver the condensed and liquefied gas from the bottom of the liquid receiving tank 144 to the expansion valve 142a at the inlet to the freezing coils 142. The top of the receiving tank 144 may be connected by means of a pipe 145 to the bottom of a condenser 146 which may be connected to the outlet connection 131 of the compressor unit. A pipe 147 may connect the inlet 130 of the compressor unit with the outlet of the freezing coils 142 and may be located at the rear of the cabinet.

Similarly to the circuit diagram of Fig. 1, I preferably provide for the refrigerator a transformer 148 which may have a primary coil 149 connected to the power mains through a thermostatic switch 150 which turns on and off the apparatus as the temperature fluctuates. Any suitable thermostatic switch may be used for controlling this operation, as, for instance, the temperature-operated device 151, which may be connected by suitable levers 152 and rapid action lever 153 to device is well understood.

One secondary 155 of the transformer may be used to energize the filamentary cathode 156 of the rectifier tube 157, the anodes 158 of which may be connected to opposite ends of the high voltage coil 159 of the transformer. The mid-tap of the secondary 159 may be connected to one side of the field coil 80, while the other side may be connected to the cathode 156 of the rectifier. A pair of condensers 160 and 161 may be used to filter out the pulsations in the D. C. supply from the rectifier. Another winding 162 on the transformer 148 may be used to supply the current for the moving coil 106, this winding being preferably connected across the end terminus of a potentiometer 163, while the moving coil 106 may be connected between one end terminal of the potentiometer and the moving arm 164. The circuit arrangement is exactly the same as described in connection with Fig. 1 with the addition of the thermostatic valve to turn on and off the operating current.

The transformer 148, rectifier tube 157 and condensers 160 and 161 may be positioned in close proximity within the mechanism compartment 140 of the refrigerator, and may be positioned within any suitable enclosure, as, for instance, the metal can 165. The controlling potentiometer may be conveniently located at the top of the cabinet, as shown, the wires for connecting it to the transformer 148 and moving coil 106 being led down to the container 165 in any convenient manner.

The potentiometer used in the circuit of Fig. 5 may be omitted if desired, as shown in Fig. 5a, by taking taps 162a off of the secondary 162 with a suitable switch 163a to select any desired tap.

The advantage of eliminating the expensive po-

tentiometer will be evident. The switch 163a may be substituted for the potentiometer 163 shown at the top of the cabinet in Fig. 4.

The circuit arrangement described above will cause the compressor to operate at a rate of sixty strokes per second when sixty cycle current is used. By a simple circuit arrangement I may double the rate of operation and a circuit diagram for such an arrangement is shown in Fig. 6. Here a transformer 166 is shown having secondaries 167 and 168 connected to the rectifier tube 169 in the same manner as shown in Fig. 5. A secondary 170 may be used to energize the moving coil through a potentiometer 171 when a double throw switch 172 is in its uppermost position. When in such position the potentiometer 171 receives sixty cycle alternating current exactly the same as in the preceding figures.

When the switch is in its lowermost position, however, the potentiometer is connected across the rectifier tube 169 through a high resistance 173 of approximately ten thousand ohms and a condenser 174, so that the potentiometer receives two direct current impulses for each cycle. The low potential side of the resistance 173 may be connected to ground through another high resistance 175, also in the order of ten thousand ohms. The low side of the rectifier may be connected through a low resistance 176 of about 300 ohms to ground.

In this arrangement I have shown an amplifier tube 177 interposed between the potentiometer 171 and the moving coil of the motor, (not shown in this figure,) and this tube may be of the 6L6 type having a filament 178 which may be energized by a separate winding 179 on the transformer 166. The cathode 180 of the tube may be grounded, while the anode 181 may be connected through the primary of a transformer 182 to the high side of the rectifier 169 through the dynamic motor field coil which is indicated at 183 and which may have a resistance of about 1000 ohms and a current carrying capacity of about 150 milliamperes. The secondary of the transformer 182 may be directly connected to the moving coil. The screen grid 184 of the tube 177 may be connected to the high side of the primary of the transformer 182, and a suitable condenser 185 may connect this point to ground. The control grid 186 of the tube 177 may be connected to the arm of the potentiometer 171.

With the arrangement just described the field for the magnet is energized by the plate and screen grid current of the amplifying tube 177 which is used to amplify the variations of potential across the potentiometer 171 before they are introduced to the moving coil. While one amplifier tube is shown, others may be used in cascade under certain conditions, and such amplifier tubes may also be used with the circuits of Figs. 1 and 5.

In using a refrigerator embodying the invention it is possible to vary the length of the stroke by adjusting the potentiometer in the moving coil circuit, as the less voltage delivered to the moving coil the smaller the force acting on it. Hence, while the frequency or reciprocation of the piston remains the same the amount of fluid which it handles may be increased or decreased, and therefore the freezing speed of the refrigerator may be changed. While I have found the circuit of Fig. 5 to be sufficient to adjust the freezing speed to a greater degree than mechanical refrigerators now in use, I have found that the speed may be greatly augmented by the circuit of

Fig. 6, wherein the frequency doubling network is used to double the frequency of reciprocation of the piston.

The compressor unit described in connection with the preceding figures has a single piston and cylinder. It may be desired, however, to provide a double acting pump, and such an arrangement is shown in Fig. 7. Here a pair of cylinders 190 and 191, each of which may correspond to the cylinder 84, already described, may be horizontally mounted on a steel plate 192 with their open ends facing each other. The cylinder 190 may be supported on a pair of legs 193 while the cylinder 191 may be supported on a pair of legs 194, these legs having feet 195 and 196, respectively, secured to the plate by suitable screws or bolts 197 and 198.

The outer ends of the cylinders 190 and 191 may be provided with valve discs 190a and 191a, respectively, which may be exactly similar to the valve disc 88 of Fig. 3, and cylinder heads 200a and 201a may be suitably secured to the cylinders by means of a plurality of bolts 202a and 203a spaced around the cylinders and engaging lugs formed on the cylinders and heads for that purpose.

The outlet connections 204a and 205a of the cylinders 190 and 191 respectively may be joined together by a T fitting 206a so that a common outlet is provided for both cylinders.

A piston 199 may have a cylindrical portion 200 at one end, adapted to have a sliding fit in the cylinder 190, and a cylindrical portion 201, at the other end, adapted to have a sliding fit within the cylinder 191. Each end of the piston is closed except for openings 202 and 203 which may be covered respectively by valves 204 and 205. The valve construction may be similar to that already described in connection with the single acting device.

The central portion 206 of the piston 199 may be larger in diameter than the diameter of the ends thereof, and portions of the walls may be cut out as at 207 and 208 to form the intake ports 45 for the piston. A coil 209 may be wound around the central portion 206 and constitutes the moving coil to reciprocate the piston.

One pole for the magnetic field for the coil 209 may comprise an internal core member 210 which is large enough in diameter so that the central portion 206 of the piston has a sliding fit thereon, and which may be provided with two extensions 211 and 212 for supporting it in position. These ends may extend axially from the midpoint 55 of the piston to a point falling within the cutout portions 207 and 208 of the piston, so that supporting posts 213 and 214 may be provided for the core which may be threaded into tapped holes in the core ends. The lower ends of the posts 213 60 and 214 may have threaded shanks which pass through holes in the plate 192 and may be secured on the lower side thereof by means of the nuts 215 and 216. The core member 210 forms one pole of the magnetic field and the supports 65 213 and 214 as well as the plate 192 form a portion of the magnetic path.

The other pole of the magnet may comprise a rectangular plate 217 provided with a hole 218 in which the coil 209 may loosely fit. This plate 70 may be supported upon a single post 219 which may be suitably secured to the plate 192 and which may be provided with a surrounding coil 220 to energize the magnetic field. The post 219 supports the plate 217 in spaced relation to the 75 core 210 and surrounding coil support 206.

I have found it expedient in assembling the double acting pump, as just described, to make the piston 199 in two parts which may be threaded together somewhere in the central portion 206, as indicated at 221. The core 210 may then be inserted in one-half of the piston before the other half is attached thereto.

The electrical connections may be made by resilient connectors 222 and 223 (Fig. 8), which may be exactly similar to those already described, 10 and connected in the same manner. The coil 209 may, in some instances, be wound in two sections, each wound in the same direction forming one coil which may be connected as already shown in Fig. 5. However, I may prefer to connect this coil in a slightly different manner. Fig. 9 shows the coil with the extreme ends connected to a potentiometer 224 which is in turn connected across a coil 225 forming the current supply secondary. The central arm 226 of the potentiometer may be connected to the midpoint 227 of the coil. By adjusting the arm on the potentiometer an adjustment of the position of the coil in the magnetic field may be obtained, and therefore an adjustment of the position of the piston. The 15 length of the stroke may also be controlled in this manner.

The double acting compressor just described may be substituted for the single acting pump of Fig. 3 by connecting the outlet T fitting 206a to 30 the resilient outlet pipe 132 and by connecting the leads of the field coil 220 to the terminals 135 and 136 and the connectors 222 and 223 to the terminals 137 and 138. Then when direct current is passed through the coil 220 the plate 35 217 becomes one pole of the magnetic field, while the core 210 becomes the other pole, and an intense field is produced in the annular space surrounding the coil 209. Alternating current in the coil 209 will cause the piston to move back and forth in the two cylinders, and, as the outlets of both cylinders are connected together, a compression pulse is produced in the compression line for movement of the piston in each direction, making one hundred and twenty pulses per second for sixty cycle alternating current.

While the invention may be preferably used in connection with a piston type compressor, I may also use it with a diaphragm compressor, as shown in Fig. 10. In this arrangement the dynamic motor 228 may be exactly the same as that described in connection with Figs. 1, 2 or 3, the moving coil being mounted on a reciprocating member 229. A rod 230 may be rigidly attached to the member 229 and may have its other end connected to the center of a diaphragm 231 which is supported on a suitable bracket 232 provided for that purpose and attached to the top plate of the motor. A compression head 233 may be mounted on top of the diaphragm leaving a small 60 compression space 234 above the diaphragm and having inlet and outlet connections 235 and 236 with suitable inlet and exhaust valves 237 and 238 respectively for controlling the movement of the fluid. As the diaphragm springs up and down alternate compression and suction will cause fluid to flow in the direction of the arrows, as will be clearly understood.

In Fig. 12 I have shown the invention incorporating a bellows type of pump. Here the motor 239 may be exactly the same as shown in connection with Fig. 10, and the pump head 240 may be similar to the head 233 of Fig. 10. Instead of the diaphragm, however, a bellows 241 may be closed at the bottom where it is attached to the 70

reciprocating power member 242 and open at its upper end where it may be secured to the head member 240 which may be supported from the top plate of the motor by means of the frame or bracket 243.

I prefer to construct the bellows in such a manner that it will provide a minimum of compression space. To this end a plurality of discs may be arranged in pairs with the discs of each 10 pair, as for instance, 242a and 243a, secured together at their outer edges by folding the edges over and welding. The lower disc 243a of one pair and the upper disc 244a of an adjacent pair may be welded at their centers to a washer 245a 15 to make a gas tight joint. The other pairs of discs may be connected similarly. All of the discs, except the bottom one, may have a small hole 246a at the center so that when the bellows is collapsed the only space left is the space in the 20 holes.

Reciprocation of the member 242 will cause the bellows to expand and contract, producing the pumping action in the compression head 240 and causing liquid or gas to flow therethrough.

While in most of the figures I have shown dynamic motors in which the field is energized by direct current and the moving coil by alternating or pulsating current, I wish to make it clear that this arrangement may be reversed, the field being supplied with alternating or pulsating current and the moving coil with direct current. In this case, however, it is preferable to laminate the magnetic circuit so as to reduce eddy currents and prevent overheating of the magnet.

I also provide a means to adjust the stroke of the reciprocating part by the use of the potentiometer (Figs. 1, 5 and 6) or the tapped transformer secondary (Fig. 5a) in the moving 40 coil circuit. I may accomplish this same result, however, if desired, by controlling the amount of current in the field coil while maintaining constant the current in the moving coil, or I may adjust the value of both simultaneously.

45 In some cases I may dispense with the field winding and use a field produced by a permanent magnet. Fig. 13 illustrates one form of a permanent magnet motor. The U-shaped member 261, center core 262 and top plate 263 are preferably made of some metal or alloy, such as an alloy of steel and cobalt, which may be highly magnetized and is capable of holding its magnetism for a long period of time. A similar annular space is provided between the core 262 55 and the plate 263, as has been illustrated in connection with the motors already described, and a moving coil 264 wound on a thin cylinder 265 is mounted for reciprocation in this space. The cylinder 265 may be attached to the piston of a 60 compressor or to any other mechanism to be driven, and the electrical connections to the coil 264 may be made in the manner described in connection with the other figures. This type of motor may be substituted, if desired, for any 65 of those illustrated.

It may be more convenient to provide an annular configuration for the magnetic field and therefore for the moving coil. The invention comprehends, however, the use of any desired 70 configuration for the field and coil, which may be made for instance, oval, square, triangular, octagonal, etc. to suit any particular construction of parts.

It will be evident from the description of the various figures that I have provided a dynamic

motor which may be used to translate electrical impulses into mechanical reciprocating or rotary motion and which may be particularly adapted for use with compressors or other reciprocating devices. I have found the motor to be 5 excellent in operating the compressor of an electric refrigerator where it has many advantages. Among these may be listed the fact that the whole apparatus may be hermetically sealed with the piston as the only moving part, and the 10 stroke of the piston may be readily adjusted by adjusting the current flowing through the moving coil. This adjustment of the piston stroke permits the output of the compressor to be varied without changing the frequency of reciproca- 15 tion, and hence freezing time in an electric refrigerator may be increased or decreased at will.

Many other variations of the invention may be used without departing from the spirit thereof, and I do not, therefore, desire to limit the invention other than by the appended claims.

What I claim is:

1. A fluid compressor unit comprising an electro magnet having pole pieces cooperating to form a tubular air gap therebetween, an elongated conductor wound in a tubular form to fit in said air gap, means to mount said conductor for reciprocation in said air gap, means to energize said electro magnet with direct current, means to pass an alternating current through said conductor, a compressor having a stationary member and a movable member, and means to operatively connect said conductor to said movable member. 25

2. A compressor comprising an electro magnet having pole pieces arranged to form a tubular air gap therebetween, a conductor wound in a tubular form to fit into said air gap, means to mount said conductor for reciprocation in said air gap, a cylinder, and a piston mounted for reciprocation in said cylinder and rigidly attached to said conductor.

3. A compressor unit comprising an electro magnet having pole pieces arranged to form a tubular air gap therebetween, an elongated conductor wound in a tubular form so as to fit into said air gap, means to energize said electro magnet with direct current, means to pass alternating current through said conductor, a cylinder supported in spaced relation from said electro magnet, and a piston mounted in said cylinder and rigidly attached to said conductor. 50

4. A compressor comprising an electro magnet having pole pieces arranged to form a tubular air gap therebetween, an elongated conductor wound in a tubular form so as to fit into said air gap, a double ended piston rigidly attached to said conductor, and a pair of cylinders, one cooperating with each end of said piston. 55

5. A fluid compressor unit comprising an electromagnet having pole pieces arranged to form a tubular air gap therebetween, an elongated conductor wound in a tubular form so as to fit into said air gap, a pumping device comprising a stationary part and a moving part, means to rigidly attach said stationary part to said electromagnet, means to rigidly attach said moving part to said conductor, a transformer having a primary adapted to be connected to a source of 70 alternating current, a secondary on said transformer, means to connect said secondary to said movable conductor, a second higher voltage secondary for said transformer, means to rectify the current produced by said second secondary, 75

and means to energize said electromagnet with said rectified current.

6. A compressor having a stationary part and a linearly moving part, an electromagnet rigidly secured to said stationary part and having pole pieces arranged to form a tubular air gap therebetween, said tubular air gap being on the axis of movement of said moving part, an elongated conductor wound in a tubular form so as to fit into said air gap, means to rigidly secure said conductor to said moving part so that reciprocation of said conductor will cause reciprocation of said moving part, means to energize said electromagnet, and means to pass current through said conductor, said means comprising at least one resilient electrical connector rigidly supported at one end on said electromagnet and at the other end on said movable conductor.

7. A compressor unit comprising a cylinder, having an open end, an electromagnet rigidly attached to said cylinder and having pole pieces arranged to form a tubular air gap therebetween, the axis of which coincides with the axis of said cylinder, and said air gap being positioned in front of the open end of said cylinder, a conductor wound in a tubular form so as to fit into said air gap, a piston mounted for reciprocation in the open end of said cylinder and rigidly attached to said conductor, so that said piston forms the support for said conductor in said air gap, means to energize said electromagnet, and means to energize said conductor, one of said means supplying pulsating current.

8. A compressor unit comprising an electromagnet having pole pieces arranged to form a tubular air gap, a cylinder mounted in spaced relation to said electromagnet and having an open end facing said electromagnet, the axis of said cylinder coinciding with the axis of said air gap, a piston mounted for reciprocation in the open end of said cylinder, a skirt on the outer end of said piston having a tubular form adapted to fit into said air gap, a coil of wire wound around said skirt, means to energize said electromagnet, and means to energize said coil, one of said means supplying pulsating current.

9. A compressor for an electric refrigerator comprising a member having a compression

chamber therein, a movable member associated with said compression chamber to alter the space therein when said movable member is moved, a conductor wound in a tubular form and operatively connected to said movable member, means to create an intense tubular magnetic field so shaped that said tubular conductor will fit therein, means to position said magnetic field so as to include said tubular conductor therein, means to energize said tubular conductor, and means to vary the energization thereof.

10. A compressor for an electric refrigerator comprising a cylinder, a piston mounted for reciprocation within said cylinder, an electromagnet having pole pieces arranged to form a tubular air gap therebetween, a tubular member attached to said piston and adapted to reciprocate freely in said air gap, a conductor wound upon said tubular member, means to energize said electromagnet, means to energize said conductor, one of said means supplying alternating current, and means to vary the current passed through said conductor.

11. An electro dynamic compressor comprising a member having a compression chamber therein, a diaphragm closing said chamber, an electromagnet having pole pieces arranged to form a tubular air gap therebetween, an elongated conductor wound in a tubular form so as to fit into said tubular air gap, said conductor being rigidly attached to said diaphragm, means to energize said electromagnet, and means to energize said conductor, one of said means supplying pulsating current.

12. A compressor comprising a member having a compression chamber therein, a bellows attached to said member and cooperating with said compression chamber so as to vary the fluid pressure therein as said bellows is expanded and contracted, an electromagnet having pole pieces arranged to form a tubular air space therebetween, an elongated conductor wound in a tubular form to fit into said tubular air space, means to operatively connect said conductor with said bellows, means to energize said electromagnet, and means to energize said conductor, one of said means supplying pulsating current.

FLORENZ J. VON DELDEN.
